UNITED STATES PATENT OFFICE.

HENRY N. HEWLETT, OF OSCODA, MICHIGAN.

LOG SKIDDING AND LOADING MACHINE.

SPECIFICATION forming part of Letters Patent No. 340,312, dated April 20, 1886.

Application filed January 13, 1886. Serial No. 189,468. (No model.)

To all whom it may concern:

Be it known that I, HENRY N. HEWLETT, of Oscoda, in the county of Iosco and State of Michigan, have invented a new and useful improvement in Log Skidding and Loading Machines, of which the following is a specification.

My invention consists in an improvement in log skidding and loading machines, hereinafter fully described and pointed out.

Figure 1 is a side elevation, and Fig. 2 a plan view, of the complete apparatus. Fig. 3 is an elevation of the drum gears. Fig. 4 is a vertical central section through the drag-rope clutch. Fig. 5 is a longitudinal section through one of the winding-drums.

1 and 3 represent strong posts or trees, which in actual operation are to be well supported by guy-ropes.

9 represents an endless track passed through blocks 7 and 8, and made endless by being secured to a carrier, 18, at the points 23 24. The endless track is stretched between trees 1 and 3 by securing the blocks 7 8 to said trees by chains or ropes, as shown in Fig. 1, and should be stretched at considerable distance from the ground, and as taut as its length and weight will permit.

In the upper part of the carrier 18 are journaled three grooved wheels, 19, 20, and 21, two of which lie above the upper half of the track and the third below and between them, thus securing the carrier firmly on the upper half of the track, and at the same time permitting the track to move through the carrier. In the lower part of the carrier is journaled a grooved wheel, 22, and from the carrier is hung by chains a spring-clutch, 33, which may be made in any known way, and which, as shown in the drawings, consists of a cylindrical piece of iron having a vertical hole through its center, and having a transverse slot therein in which lie—one on each side of the center—two jaws, 38 and 39, which are constantly pressed together by two springs, 40 and 41, acting on pins 42 and 43 in said jaws. The meeting ends of jaws 38 39 are beveled back from their top-surfaces, as shown, and are cut out in the form of a half-circle, to prevent said jaws from wearing the drag-rope.

Any known means of forcing the jaws 38

39 apart at will may be used, and any form of spring-clutch may be substituted for the one shown.

5 represents a boiler and one or more steam-engines mounted on a frame, which may be provided with wheels for portability, and the engines are connected with a crank-shaft, 27, on which is secured a pinion, 35.

34 and 36 represent gear-wheels mounted rigidly on two shafts journaled in the frame which carries the crank-shaft—one on each side of said crank-shaft—so that said gear-wheels each mesh in the pinion 35, and 37 is a similar gear-wheel mounted on a fourth shaft and meshing with gear-wheel 36, so that the motion of pinion 35 drives all of said shafts. Fastened to each gear-wheel is a friction-clutch of any known type, and on each shaft is a loose drum adapted to be locked to the friction-clutch, two of said drums being represented by 26 and 28.

Any known method of forcing the loose drums into contact with their friction-clutches may be used, and the drawings indicate the common method of a screw, which acts on one end of the drum.

On the shaft which carries gear-wheel 37 I put two loose drums, as shown in Fig. 5, to permit said shaft to actuate two ropes instead of one, and thereby save multiplication of shafts. I do this by attaching a friction-clutch, 45, to gear-wheel 37, and a similar clutch, 46, to the other end of the shaft, and by placing a loose collar, 44, on said shaft between the winding-drums. This collar 44 is connected with the screw mechanism by a rod, 47, lying and sliding in a hole bored in the shaft and connected with the collar by a pin, 54, which passes through said rod and a slot, 55, in the shaft into the collar. The outer end of rod 47 is provided with shoulders 51 52, between which fits a block, 50, connected with the screw 48, provided with the actuating crank 49, so that said screw can reciprocate said rod 47 and yet permit said rod to turn with the shaft. By forcing collar 44 in one direction friction-clutch 46 will be brought into play, and in the other direction friction-clutch 45 will act, so that either or neither of the winding-drums can be rotated at will.

11 represents a pulley secured to tree 1, about on a level with the lower half of track 9; and

10 represents a drag rope which runs from drum 26 through pulley 11, thence through pulley 22 on the carrier, and through spring-clutch 33, and its end is fastened to a pair of tongs, 17, or provided with a chain, if preferred, by which it can be fastened to a log, 4. Below the spring-clutch 33 a tapering piece of metal, 53, is fastened on the drag-rope of such shape that when drawn up into the spring-clutch it will separate the jaws 38 39, but will not descend through said jaws, as will be readily understood from Fig. 4. If desired, the drag-rope may have a cord, 56, connected therewith in any suitable manner above the spring-clutch 33, for the purpose of raising the dog 53 to separate the jaws 38 and 39 when required.

12 represents another pulley fastened to tree 1, about on a level with the upper half of track 9; and 29 represents a rope which runs from drum 28, through pulley 12, and is spliced or fastened to the upper half of said track at a point which is close to block 8 when carrier 18 is close to block 7. I prefer to equip each shaft or winding-drum with a common friction-brake, or any other desirable brake, so that the engineer can check and hold it; but as such brakes are well known I have not deemed it necessary to show them in the drawings.

The operation of my invention is as follows: The engine-frame being set in position and the track 9 being stretched between trees 1 and 3, the carrier 18, carrying with it the drag-rope 10, is run out to the end of the track by winding in rope 29, which draws the upper half of track 9 toward block 8, and of course moves the lower half of the track, in which is carrier 18, in the contrary direction. When the carrier is at the end of, or other desired point on, the track-drum 28, which actuates rope 29, is stopped, leaving the carrier stationary. The end of drag-rope 10 is now carried to a log which it is desired to haul in, and the tongs 17 attached to said log. Drum 26 is now clutched to its shaft and the drag-rope hauled in, bringing with it the log to which it is attached, 4. When the log comes under the carrier, it is raised from the ground, either wholly or at one end, until the dog 53 passes above the spring-jaws 38 39, when the log is held suspended by said jaws, and the continued motion of the drag-rope hauls in the carrier, 53, bringing with it the log. When the log has been brought to the place desired, the spring-jaws 38 39 are unlocked and the log laid on the skid or ground by easing off on the drag-rope. It is evident that as the carrier comes in the rope 29 goes out to an equal extent, in readiness to again carry out the carrier.

32 represents a track, on which is a car, 6. To load logs on this car after they have been brought in by the skidding-machine, I use a 65 duplicate of the apparatus already described,

but on a smaller scale, 1 and 2 representing the trees, 13 and 14 the blocks which carry the endless track, 15 the carrier, 31 the drag-rope, corresponding to 10, and 30 the outhaul-rope, corresponding to 29. 16 represents tongs 70 attached to drag-rope 31. As the ropes 30 and 31 are comparatively short, they can be operated by a single shaft carrying two loose drums, and this is provided for by the construction shown in Fig. 5, in which the two 75 short drums serve to operate the ropes 30 and 31.

The operation of the loading device is precisely like that of the skidding device hereinbefore described, the drag-rope 31 picking up 80 a log from the place where it has been put by the skidding-machine, raising and holding it suspended, and laying it on car 6.

I am aware that the use of carriers running on suspended tracks and carrying drag-ropes, 85 by which a weight can be raised and then drawn in over the track, is quite old, and has been used in carrying water, hay, logs, &c., and therefore do not claim the same.

What I claim as my invention, and desire to 90 secure by Letters Patent, is—

1. In combination with an endless track stretched between two supports, a carrier secured to and moving with said track, a drag-rope running through a pulley on said carrier 95 and running through a spring-clutch suspended from said carrier, an outhaul-rope secured to the half of the track not fastened to the carrier, and suitable winding devices for operating said drag and outhaul ropes, substantially as shown and described.

2. In a log-skidding machine, the combination of the endless track 9 with the carrier 18, the opposite ends of said track being firmly secured to said carrier to move the carrier back and forth, substantially as shown and described.

3. In combination with the drag and outhaul ropes of a log-loading machine, a shaft having therein two loose drums, two friction-clutches, 45 46, rigidly connected to said shaft, a loose collar between said drums, and mechanism, substantially such as described, whereby said collar can be moved in either direction, substantially as shown and described.

4. The combination of the endless track 9, carrier 18, having the opposite ends of said track firmly secured thereto, and outhaul-rope 29, substantially as shown and described.

5. In combination with the endless track 9, 120 the carrier 18, having the two ends of the track firmly secured thereto, and having thereon the wheels 19, 20, and 21, and the blocks 7 and 8, provided with means of attachment to supports, substantially as shown and described.

HENRY N. HEWLETT.
